UNITED STATES PATENT OFFICE.

CHARLES D. YOUNG, OF PHILADELPHIA, PENNSYLVANIA, ASSIGNOR TO Q & C COMPANY, OF NEW YORK, N. Y., A CORPORATION OF MAINE.

GUARD-RAIL STRUCTURE.

Application filed May 15, 1924. Serial No. 713,392.

The present invention relates to guard rails for railways and has for its object to produce a guard rail structure adapted to be more economically manufactured and 5 to possess other important advantages over the types of guard rail structures as at present employed.

A characteristic and important feature of my improved guard rail construction consists in an improved design thereof wherein the guard rail proper and its supporting base are formed as an integral structure of a cross-section to allow of it being produced mainly by a rolling operation. The improved construction is further designed to obviate the necessity of employing supplementary securing devices, such as the customarily used guard rail clamps whereby the installation is materially simplified and 20 other important advantages obtained.

The described and other features and advantages of my present invention will be understood by reference to the accompanying drawing wherein like reference numerals 25 are applied to corresponding parts in the several views.

In the drawing:

Fig. 1 is a plan view of a guard rail installation made in accordance with the 30 present invention.

Fig. 2 is a view in side elevation.

Fig. 3 is a view in end elevation showing the improved guard rail of Fig. 1 as rolled and prior to the bending of the base portion 35 into final position.

Fig. 4 is an end elevation of the structure of Fig. 1 as completed and installed and taken on line 7—7.

In accordance with my present invention, 40 the guard rail is rolled as an integral or unitary structure having a base flange of sufficient width or extension to underlie the track rail and provide a bearing therefor. To this end the guard rail may be rolled of a cross-section as best illustrated in Fig. 4, wherein 20 indicates the track rail and 16 the guard rail to be secured in the usual spaced relation thereto. The guard rail of my improved form is rolled of the section 45 as illustrated in Fig. 3 having the upper head portion 16, vertical web portion 17 and the base flange 19. The section as it comes from the rolls has the flange extension 50 19 in substantially parallel relation to the vertical axis of the rail section and the com-

pleted form, as shown in Fig. 4, is produced by bending or turning back of the vertical extended portion 19 of the base flange into a horizontal position underlying the rail base 18. The bearing extension flange is 60 of such length as to underlie and receive thereon the track rail 20 and may furthermore and as illustrated be stamped out intermediate of the ties to lighten the structure. Suitable punching is provided at 65 21—22 to receive the track rail securing spikes which likewise function to secure the guard rail in its proper spaced relation. The end portions of the guard rail proper are suitably deformed from the rail section 70 to provide in the finished structure outwardly flared ends 23 having their upper surfaces downwardly inclined; this being accomplished by a forging or pressing operation subsequent to the rolling of the sec- 75 tion to the form illustrated.

The guard rail thus produced is relatively inexpensive from the standpoint of commercial manufacture in that it is adapted to be produced mainly by a rolling operation and is further particularly advantageous in that its method of securing is such as to more effectively resist longitudinal pressures whereby the creeping tendency is more effectively resisted. The provision of 80 the guard rail and the securing and supporting plate as an integral structure offers the important advantage of ample security from the standpoint of strength and in the installation has a relative permanency which 85 contributes largely to economy by reducing maintenance costs.

Having described my invention I claim:

1. As a new article of manufacture a rolled steel guard rail section having head, 95 web and base portions, said base portion having a horizontal flange extension bent inwardly into horizontal position to underlie the guard rail section and at its outer end to provide a base support for the track rail, 100 substantially as described.

2. As a new article of manufacture a rolled steel guard rail section having head, web and base portions, said base portion having a horizontal flange extension bent 105 inwardly into horizontal position to underlie the guard rail section and at its outer end to provide a base support for the track rail, said flange extension having punched out portions spaced with relation to the 110

2

ties, and said guard rail section having its upper portion deformed to have outwardly flared and downwardly inclined end portions.

3. The herein described method of producing a guard rail structure which consists in rolling a guard rail section having head, web and base portions with the base portion having a flange extension substantially in

parallel relation to the web and to complete 10 said structure by bending said flange extension into horizontal position to underlie the base portion and deforming the upper portion of the rolled section by forging to provide outwardly flared and downwardly 15 inclined end portions, substantially as described.

CHARLES D. YOUNG.
